WATER CONDITIONER

Robert A. Schaefer, Culver City, Calif., assignor to Hydrocon, Inc., Culver City, Calif., a corporation of California

Application July 25, 1958, Serial No. 51,935

Term of patent 14 years

(Cl. D91—1)

FIG. 2.

FIG. 1.

FIG. 3.

FIG. 4.

FIG. 8.

FIG. 5.

FIG. 6.

Fig. 1 is a perspective view of a water conditioner showing my new design;

Fig. 2 is a front elevational view thereof;

Fig. 3 is a top plan view thereof;

Fig. 4 is a bottom plan view thereof; and

Fig. 5 is a transverse sectional view thereof taken on line 5-5 of Fig. 2, through the opening for inserting a sacrificial metal element;

Fig. 6 is a transverse sectional view thereof taken on line 6-6 of Fig. 2;

Fig. 7 is a transverse sectional view thereof taken on line 7-7 of Fig. 2; and

Fig. 8 is a transverse sectional view thereof taken on line 8-8 through the inspection port.

Fig. 1 is drawn on a slightly reduced scale.

I claim:

The ornamental design for a water conditioner, substantially as shown.
